PAPER TOWELING

Nicholas Sidjakov, Sausalito, Calif., assignor to Fort Howard Paper Company

Filed Apr. 19, 1971, Ser. No. 135,537

Term of patent 14 years

Int. Cl. D5—03

U.S. Cl. D59—2

The figure is a plan view of paper toweling showing my new design, a full width of the design being shown with the design unit repeating in regular succession to an indeterminate length, the background configuration of the paper towel being shown at the lower left-hand corner, the remainder of the background having been omitted for convenience of illustration.

The drawing has been lined for color.

I claim:

The ornamental design for paper toweling, as shown and described.
